UNITED STATES PATENT OFFICE.

ISAAC T. MONTROSS, OF PEEKSKILL, NEW YORK.

DESIGN FOR A STOVE.

SPECIFICATION forming part of Design No. 11,957, dated August 24, 1880.

Application filed June 23, 1880. Term of patent 7 years.

To all whom it may concern:

Be it known that I, ISAAC T. MONTROSS, a citizen of the United States, residing at Peekskill, in the county of Westchester and State 5 of New York, have invented and produced a new and original Design for Stoves, of which the following is a specification.

In the accompanying drawing is given a perspective view of my newly-designed stove. 10 The leading feature of my design consists in a series of band-like surfaces or rings which surround the stove at intervals, indicating the divisions or chambers of the stove; but a scarcely less important feature is a metal band, 15 either polished or plain, which surrounds the dome section of the stove at about its middle. There are also minor original features, as the corrugations surmounting the polished band-like surfaces or rings before mentioned, the 20 Gothic doors of the combustion-chamber, the downwardly-flaring or bell-mouthed shape of the wall of the ash-chamber, the approximately semi-spherical cap and its surmounting urn having the peculiarly-formed handle, and 25 the polished knobs of the hinge-pintles, all of which will be definitely pointed out in the following description and appended claims.

The band-like surface indicated by the numeral 1 is the edge of the stove-base A, and 30 on the top margin of this base is formed an annular series of horizontal corrugations, a, the ends of which give an undulating top edge to the band a. Next above the base A is the ash-chamber B, the wall of which expands or flares downwardly like the mouth of 35 a bell, and is provided with a door, as usual. Surmounting the ash-chamber is a molding, upon which is formed the band-like surface 2, immediately above but setting back a little 40 from the edge of which is an annular series or belt of upright corrugations, b. Mounted upon this molding is the fire-pot chamber C, the wall of which is formed by four doors, c, hinged to suitable posts and provided with arched 45 openings for mica panels.

The combustion-chamber D sets upon the top edge of the chamber C, and its lower edge projects and overhangs said chamber C, and has formed upon its lower margin the band-like surface 3, which indicates the dividing- 50 line between the two chambers. The cham-

ber D contracts upwardly, and its wall is mainly formed by four doors, d, having openings of Gothic design for mica panels, said openings having each two side ribs parallel 55 with each other up to an arch, d', and then converging so as to meet above said arch.

Placed upon the top of chamber D is an overhanging rim bearing the band-like surface 4, and adjoining this surface 4 is the series of 60 horizontal corrugations e, giving the band 4 an undulating upper edge. Upon this overhanging rim sets the dome E, surrounded about mid-height by the band or belt F, bearing ornamental tracery, and also, in the present instance, the name of the stove, "Avalon;" but this may, of course, be changed, and the tracery omitted, if desired, without varying essentially the aesthetic effect of the design, the distinguishing features of which 70 are the two ribs F', extending parallel with each other about three-quarters of the way round the dome, and then spreading apart, as at F', so as to leave a space for ornamental tracery and for the name. 75

The band or belt F is preferably polished or bright; but that is not essential. Upon the top of the dome E is placed an overhanging rim bearing the band-like surface 5, adjoining above a series or belt of horizontal 80 corrugations, f, and upon this rim is placed the approximately semi-spherical cap G, ornamented by tracery and a belt or band of corrugations, g, and surmounted by the urn H. The urn H is provided with a highly-ornamental handle formed by the vertical bars i, arranged diametrically opposite each other, projecting above and below the brim of the urn and intersected by the oblique bars k, which join at their tops a tablet, l, bearing in 90 the present case an ornamental letter, "A," which is the initial letter of the name of the stove. The vertical bars i do not stop at their points of intersection with the oblique or inclined bars k, but extend upward to about a level 95 with the tablet l, and have ornamental upper ends, thus producing a more fanciful design than if they terminated at their point of intersection with the bars i. The letter may, however, be omitted or replaced by another 100 design.

The pintles of the hinges of the doors of the

ash-chamber, fire-pot chamber, and combustion-chamber are provided at their tops, respectively, with polished knobs m m' m'' , which contribute greatly to the general effect of the design.

5 It will be understood that the band-like surfaces or rings may be polished or ground or not, as desired, and the annular belts of corrugations may be polished either wholly or upon their ends only, or not polished at all, and they may be omitted without materially affecting the general effect of the design as a whole.

What I claim is—

15 1. The design for a stove, consisting of the urn having the handle composed of the vertical bars i and oblique intersecting bars k , connected at their tops, the said vertical bars being extended above the oblique bars, as shown.

20 2. The design for a stove, consisting of the band-like surfaces 1 2 3 4 5, surrounding the stove at intervals, and the polished metal belt or band F, surrounding the dome E, said band or belt having ribs F' extending parallel with each other about three-quarters of the way round the dome, and then spreading apart, leaving an enlarged space partially occupied by tracery and the name by which the stove 25 is designated, as shown.

3. The design for a stove, consisting of the contour specifically described and shown from band-like surface 1 to band-like surface 2, inclusive.

4. The design for a stove, consisting in the 35 combustion-chamber section shaped as shown between the band-like surfaces 3 and 4, and provided with Gothic doors with the arches d .

5. The design for a stove, consisting of the combination of shapes shown and described, 40 from the band-like surface 1 to the top of the urn, the whole supported on legs, as shown.

6. An overhanging rim upon the top of the stove-dome bearing the band-like surface 5, the contiguous series or belt of horizontal radial corrugations f , the approximately spherical cap G, and the annular series or belt of corrugations g , as shown.

7. The design for a stove, consisting of the band-like surfaces 1 2 3 4 5, surrounding the 50 stove at intervals, and the annular series or belts of corrugations a b e f , arranged with relation to the band-like surfaces 1 2 3 4 5 as shown.

In testimony whereof I have hereunto set 55 my hand in the presence of two witnesses.

ISAAC T. MONTROSS.
